MERRY-GO-ROUND

Carl L. Hannas, St. Paul, Alberta, Canada

Application December 4, 1957, Serial No. 700,581

3 Claims. (Cl. 272—33)

This invention relates to a merry-go-round and more particularly a merry-go-round for children.

It is an object of the present invention to provide a merry-go-round for children having self-contained means for propelling the merry-go-round about a single vertical column.

Another object of the present invention is to provide a merry-go-round having a plurality of depending carriages for supporting children in circumferentially spaced relationship, each such carriage having self-containing driving and braking means for controlling the movement of the entire merry-go-round.

Still another object of the present invention is to provide a merry-go-round of the above type which can be made in substantially any desired size so as to accommodate any desired number of occupants thereon.

Other objects of the invention are to provide a merry-go-round bearing the above objects in mind which is of simple construction, has a minimum number of parts, is inexpensive to manufacture, efficient in operation and safe for children to use.

A merry-go-round according to my invention comprises a vertical support carrying bearing means adapted to rotate about the support on its upper end and at least one pair of arms extending from the bearing means. A single suspension member is connected to the outer end of each arm by a first hinge permitting centrifugal motion, and a second hinge permitting circumferential motion of the suspension member. A carriage is fastened to the lower end of each suspension member, each carriage having a pair of treadles. A crank shaft having two oppositely positioned cranks is fastened to the vertical support and extends through and above the bearing means. Cable means are provided to connect the treadle of each carriage to the second crank, whereby motion of the treadles causes the carriages to rotate about the vertical support.

In drawings which illustrate one embodiment of the invention:

Figure 1 is an elevation of a merry-go-round constructed according to my invention.

Figure 2 is a top view of the embodiment shown in Figure 1.

Figure 3 is a side view of one of the carriages with its associated suspension member and arm.

Figure 4 is a detail showing the arrangement of cables and sheaves at the outer end of one arm.

Figure 5 is a sectional view taken on the line 5—5 of Figure 4.

Figure 6 is a sectional view taken on the line 6—6 of Figure 4.

Figure 7 is an end view of the arm shown in Figure 4.

Figure 8 is a sectional view taken on the line 8—8 of Figure 1, and

Figure 9 is a sectional view taken on the line 9—9 of Figure 8.

Referring to Figure 1, a merry-go-round 11 made in

2

accordance with the present invention is shown to include a vertical support 13 that may be embedded in the ground 14 or otherwise supported thereon in a suitable manner. A crownlike bearing unit 16 having a central thrust bearing 17 rotatably supported adjacent to the top of the column 13, is provided with a plurality of equally spaced apart radially outwardly and upwardly diverging pairs of arms 18. Each pair of arms 18 supports a separate carriage 19 and operating structure for propelling the merry-go-round as will be hereinafter described.

With particular reference to Figures 2 and 3 of the drawing, it will be noted that each carriage 19 is carried upon the lower ends of a supporting member having a pair of relatively rigid support rods 20 that are pivotally connected at their upper ends to a shackle 21 which is supported for rotation about a horizontal axis normal to the supporting arms 18 by means of a pivot pin 22. While the carriage itself may be of any desired shape and configuration, it is shown in the drawing to include a seat 24, a handle 25, and a vertical partition wall or panel 23 which effectively separates the treadles 26 for safety purposes. In place of the handle 25, the carriage 19 may be provided with a hoop that may be hinged to the front of the carriage for movement between a normal horizontal position and a raised position to enable the child to get into and out of the carriage, but providing a back rest and safety ring for the children when the device is in use so as to prevent the children from falling off the carriage.

The rear end of each treadle 26 is pivotally connected to the carriage by means of a hinge 27, while one end of a cable 29 is connected to each of the forward ends of the treadles on each carriage. These cables 29 extend upwardly into engagement with pulleys 30 which are rotatably supported upon a pulley shaft 31 carried by the respective supporting arms 18. Guide sheaves 32 further guide the cables 29 into association with the drive mechanism that includes a pair of eccentric circular crank plates 33, 34 located at diametrically opposite sides of the vertical longitudinal axis of the column 13 and their associated mounting disc 36. The clevis 35 which supports the guide sheaves 32 is secured to the arms 18, as is more clearly shown in Figures 4 and 5. A loop guide 28 carried by the shackle 21 guides the cables 29 into engagement with the initial guide pulleys 30. As the bearing unit 16 is rotated about the vertical column 13, the cables 29 which are connected to the cranks 33 and 34 will be reciprocated back and forth, and alternately raise and lower each of the treadles 26. Conversely, in response to the reciprocation of the treadles 26, the unit can be made to rotate about the column 13 through the cooperative working of the treadles by the children carried upon each of the carriages 19. Of course, as the speed of rotation increases, the carriages 19 will be moved by centrifugal force to the radially outwardly disposed positions shown in broken lines in Figure 1.

The pivotal connection between the suspension member consisting of rods 20 and the shackle 21 permits the carriage 19 to move backward and forward along the line of travel of the carriage 19. The combination of forward and backward motion along the line of travel and centrifugal motion ensures that the combined load of the carriage and its rider will be suspended through its centre of gravity. This also ensures that all forces acting on the rider will be colinear with the axis of the support member and no undesirable torque couples will be developed. If the resultant force acting on the rider and carriage were not colinear with the support member, then the rider would tend to be thrown from the carriage when the merry-go-round accelerates.

While a reverse pressure upon the treadles may be used

to halt the unit, a manually operable brake assembly is carried upon the unit for the individual control of each of the occupants. This brake mechanism includes a brake drum 40 which is secured to the column 13 and a brake shoe 42 secured to one end of a bell crank 43 that is carried upon a bracket 45 secured to each pair of arms 18. Each bell crank is supported for movement about the associated pivot pin 44 in response to a pull upon the connecting rope 47 that extends between the opposite end of each bell crank and the associated carriage 19. It is thus possible for each individual child to stop the movement of the unit whenever desired.

What I claim as new and desire to protect by Letters Patent of the United States is:

1. A merry-go-round comprising, a vertical support, bearing means on the upper portion of said support adapted to rotate about said support, at least one pair of arms extending from said bearing means, a single suspension member connected to the outer end of each arm by a first hinge permitting centrifugal motion of the suspension member and a second hinge permitting circumferential motion of the suspension member, a carriage fastened to the lower end of each suspension member

each carriage including a pair of treadles, a crank shaft having two oppositely positioned cranks fastened to said vertical support and extending through and above said bearing means and cable means connecting one treadle of each carriage to one crank and the other treadle of each carriage to the second crank whereby motion of the treadles causes the carriages to rotate about said vertical support.

2. A merry-go-round according to claim 1 wherein the said cranks are formed as discs having their flat sides parallel to the cable means connecting to crank pins.

3. A merry-go-round according to claim 2 including a brake drum on said vertical support, a brake shoe mounted on said bearing means and adapted to bear against said brake drum, and brake shoe operating means adjacent each carriage.
